UNITED STATES PATENT OFFICE

JOSEPH F. SCHILLER AND WALTER W. WESCOTT, OF PHILADELPHIA, PENNSYLVANIA,
ASSIGNORS OF TWO-THIRDS TO SAID JOSEPH F. SCHILLER AND ONE-THIRD TO SAID
WALTER W. WESCOTT

APPARATUS FOR STERILIZING AIR

Application filed January 8, 1923. Serial No. 611,542.

There is a wide field for use of pure sterilized air especially when used under compression. It may be used for loading or unloading milk or other liquids in which freedom from bacteria or other impurities is required, cleansing tanks, pipes, cans or bottles, drying and cooling bottles, and for a variety of like purposes for which ordinary compressed air is not permissible because of its impurity. We have discovered that by comparatively simple means air may be so sterilized and purified that it may be used for transferring milk not only without contaminating the milk but with a resulting decrease in the bacteria content, and that it may be used to great advantage for the purposes above mentioned.

The object of our invention is to provide a simple apparatus for so purifying air and our invention consists in the apparatus hereinafter described and claimed.

Figure 1 is a side elevation showing the preferred form of our apparatus, a part of a storage tank being shown in section,
25 Figure 2 a vertical section of an expansion tank,

Figure 3 a vertical section of an oil separator,

Figure 4 a central section of an air-filtering device,

Figure 5 a section on line 5—5 of Figure 4, and

Figure 6 a section on line 6—6 of Figure 4. The numeral 1 indicates an air compressor which may be of any usual type, 2 the intake pipe, 3 the starting unloader, 4 the air outlet pipe which leads to the top of an expansion tank 5, shown as of cylinder form and about four times as large as pipe 4, 6 a pipe connecting the lower end of tank 5 with a second expansion tank 7, the top of which is connected by a pipe 8 with the top of a third expansion tank 9 which is connected by a pipe 10 with the top of a receiving tank 11. 45 A pipe 12 leads from the receiving tank to an oil separator 13, which may be of the type used for separating oil from steam. From the oil separator a drain pipe 14 leads to a trap 15. A pipe 16 leads from the oil separator to a filter 17, shown as of double type.

The filter consists of a spider 18 having a central bore 19, two pairs of cylindrical parts 20 and pipe connections 21. The cylindrical parts 20 are adapted to receive sleeves 22 which are packed with wool adapted for filtering purposes. The sleeves are perforated, as indicated at 23, in that part of their periphery which is in alignment with the bore 19 to afford passage for the air. A pipe 24 leads from the filter and is provided at its free ends with a valve 25 and with means for connection with a pipe 26, which may be flexible, leading to the point of use.

In use we preferably compress the air so that its temperature rises about 100° F. above atmospheric temperature, and expanding it within the tanks until it drops about 70° F. As the air passes to the discharge pipe, it cools to atmospheric temperature. The sudden rise in temperature and the cooling by expansion creates an action in the air which destroys the bacteria and thus sterilizes the air under pressure. It is found from analysis that the air after having passed through our improved apparatus in the manner described is sterile and free from impurities.

While we have described our invention as taking a particular form, it will be understood that the various parts of our invention may be changed without departing from the spirit thereof, and hence we do not limit ourselves to the precise construction set forth, but consider that we are at liberty to make such changes and alterations as fairly come within the scope of the appended claims.

Having thus described our invention, what we claim as new and desire to secure by Letters Patent is:—

1. An apparatus for sterilizing air comprising means for compressing air a plurality of tanks of gradually increasing volume, conduit connections between the tanks and the compressor means, and flow control means in each of said connections whereby the compressed air may expand through successive stages.

2. An apparatus for sterilizing air comprising means for compressing air, means for filtering the air prior to compression, a plurality of tanks of gradually increasing vol-

ume, conduit connections between the tanks and the compressor means, and flow control means in each of said connections whereby the compressed air may expand through successive stages.

5   3. An apparatus for sterilizing air comprising means for compressing air, means for filtering the air prior to compression, a plurality of tanks of gradually increasing
10 volume, conduit connections between the tanks and the compressor means, flow control means in each of said connections whereby the compressed air may expand through successive stages, and means for refiltering the air after its passage through the said tanks.

15   In testimony whereof we have signed our names to this specification.

JOSEPH F. SCHILLER.
WALTER W. WESCOTT.
